(57) **CLAIM**

The ornamental design for an insect repellent, as shown and described.

DESCRIPTION

FIG. 1 is a front perspective view of an insect repellent showing my new design;

FIG. 2 is a front view of the insect repellent shown in FIG. 1 (with the rear side being a mirror image thereof);

FIG. 3 is a side view of the insect repellent shown in FIG. 1 (with the other side view being a mirror image thereof);

FIG. 4 is a top view of the insect repellent shown in FIG. 1; FIG. 5 is a bottom view of the insect repellent shown in FIG. 1; and,

FIG. 6 is a front perspective view of the insect repellent shown in FIG. 1, shown in the environment of a cylindrical pole. The broken lines depicting the end portions of the insect repellent and the cylindrical pole show unclaimed subject matter.
